Primary Examiner — Ricky Pham(74) *Attorney, Agent, or Firm* — Loeb & Loeb LLP(57) **CLAIM**

The ornamental design for an articulable pan handle, as shown and described.

DESCRIPTION

FIG. 1 is a front elevational view of an embodiment of an articulable pan handle.

FIG. 2 is a side elevational view of the articulable pan handle of FIG. 1, the opposite side being a mirror image thereof.

FIG. 3 is a top plan view of the articulable pan handle of FIG. 1.

FIG. 4 is bottom plan view of the articulable pan handle of FIG. 1; and,

FIG. 5 is perspective view of the articulable pan handle of FIG. 1.

The broken lines appearing in the figures are for the purpose of illustrating the environmental structure of the article of the claimed design and form no part of the claimed design.
